TELEPHONE TIMER STAND

Hugh O. Pessner, 90 Corte De Sabla,
Greenbrae, Calif. 94904

Filed Sept. 3, 1971, Ser. No. 177,926

Term of patent 14 years

Int. Cl. D10—03; D14—03
U.S. Cl. D26—14 A

FIG. 1 is a front isometric view of a telephone timer stand, the broken lines representing the conventional telephone are shown for illustrative purposes only;

FIG. 2 is an isometric view of the top, back and opposite side thereof, with the telephone instrument removed; and

FIG. 3 is an isometric view of the bottom, back and side thereof.

I claim:

The ornamental design for a telephone timer stand, as shown and described.
